Primary Examiner — Steven J Czyz(74) *Attorney, Agent, or Firm* — The Dobrusin Law Firm, PC(57) **CLAIM**

The ornamental design for a sealing device, as shown and described.

DESCRIPTION

FIG. 1 is a perspective view of the present invention in an installed state.

FIG. 2 is a front elevational view of the embodiment shown in FIG. 1.

FIG. 3 is a rear elevational view of the embodiment shown in FIG. 1.

FIG. 4 is a top-down view of the embodiment shown in FIG. 1.

FIG. 5 is a bottom-up view of the embodiment shown in FIG. 1; and,

FIG. 6 is a mirror image side profile view of the embodiment shown in FIG. 1.

The broken lines showing environment in the drawings are for illustrative purposes only and form no part of the claimed design.
